RIBBON FEEDING AND INKING MECHANISM
FOR TYPEWRITING MACHINES

John L. Petz, Rochester, N. Y., assignor to International Business Machines Corporation, New York, N. Y., a corporation of New York

Application February 15, 1945, Serial No. 578,052

1 Claim. (Cl. 197—168)

1

This invention relates to typewriting machines. The primary object of the present invention is to provide a novel inking mechanism for typewriters and other office machines.

An object is to provide an inking mechanism which avoids the use of fabric inking ribbons which must be impregnated with ink prior to insertion in the machine.

An object is to provide an inking mechanism in which it is possible to change the ribbon without soiling the fingers.

An object is to provide an inking mechanism which is considerably simpler and more reliable than ordinary ribbon feed mechanisms by reason of the elimination of the ribbon reversing feature.

An object is to provide an inking mechanism which employs an ink transfer member which may consist of a ribbon which is kept uniformly inked while the machine is in use.

An object is to provide an inking mechanism which may utilize ordinary printers' ink.

Other objects of the invention will be pointed out in the following description and claim and illustrated in the accompanying drawing, which discloses, by way of example, the principle of the invention and the best mode, which has been contemplated, of applying that principle.

The single figure is a perspective view of a portion of a typewriting machine to which the inking mechanism forming the subject of the present invention is shown applied.

In the drawing, the numeral 1 designates the base of a conventional typewriter well known in the art as the "Electromatic." It will be understood, however, that the inking mechanism may be applied to other machines just as readily as for the one selected for purposes of illustration of the invention. Type bars like the type bar 2 are mounted in the usual segment 3 to which is attached the type guide 4. Slidably mounted on the type guide is the usual ribbon vibrator 5 which is located in front of the card guide 6. The card guide is located in front of the platen 7 which is mounted in the carriage (not shown) in the usual way. The type bars are controlled by the keys 8 and are operated by a power roller 9 which is selectively coupled to the type bars by means of the keys 8 in a well known way.

The ribbon mechanism includes an ink pot 9 which is secured to the left-hand side of the base 1 and contains an ink pick-up roller 10 which is rotatable in suitable bearings in the ink pot 9. The roller 10 dips well below the level of the ink in the ink pot 9 so as to be always capable of picking up ink. The shaft 11 of the roller 10

extends outside of the ink pot 9 and has secured to it a bevel gear 12 which meshes with a bevel gear 13 secured to a vertical shaft 14. This shaft is journaled in a pair of brackets 15 secured to the side of the base 1 and at its lower end has secured to it a pinion 16 which meshes with a worm 17 fixed to a shaft 18 journaled in the base 1 by any suitable means. The shaft 18 extends interiorly of the base 1 and has secured to it a friction roller 19 which engages the surface of the power roller 9. Since the power roller 9 rotates continually while the machine is in use, it is evident that the ink pick-up roller 10 will likewise be continually turning and have its surface continually covered with a film of ink. The gearing is such that the roller 10 rotates relatively slowly compared to the power roller 9 in order to avoid throwing off the ink by centrifugal force. Cooperating with the roller 10 is a doctor blade 20 which is arranged to spread the ink evenly on the roller 10. Also coacting with the roller 10 is an ink spreading roller 21 which is journaled in the ink pot 9 and driven by the roller 10 through gears 22 secured to the shafts of the rollers 10 and 21, respectively. Also journaled in the ink pot 9 is an ink transfer roller 23 and secured to its shaft is a gear 24 which meshes with the gear 22 secured to the roller 21. The gears 22 and 24 are located outside the ink pot 9.

Pivoted on a bracket 25, which may be formed as a part of the ink pot 9 or separately attached thereto, is a lever 26 having pivoted near its front end a pressure roller 27 disposed above the roller 23. The roller 27 is actuated toward the roller 23 by a toggle spring 28 interposed between a pin carried by the base 1 and a pin carried by the rear arm of lever 26. Normally toggle spring 28 urges the lever 26 in a clockwise direction but, when it is desired to change the ribbon, the lever 26 may be raised by hand, by means of a finger piece 26a, far enough to permit the toggle spring 28 to swing the lever 26 in the other direction and hold it in released position by reason of lever 26 engaging the rear side of the ink pot 9.

Secured to the base 1 are the rear ribbon guide members 29 disposed on opposite sides of the ribbon vibrator 5 just in front of the platen and a little below the level of the usual loops in the ribbon vibrator through which passes the inking ribbon. Secured to the front plate 30 is a second pair of front ribbon guides 31 and a guide finger 32 which is located at approximately the center of the plate 30.

The guides 29 and 31 support an ink transfer ribbon 33 which passes in front of finger 32 and

through the usual loops in the ribbon vibrator 5. The ribbon 33 also is twisted horizontally at the left-hand side of the machine between the left-hand guides 29 and 31 and passes between the transfer roller 23 and the pressure roller 27 which serves to keep that face of the ribbon which confronts the platen 1 at the ribbon guide 5 firmly against the surface of the transfer roller 23. Since the direction of rotation of the roller 10 must be clockwise to render the doctor blade 26 effective, it is evident that the roller 23 likewise will be rotated clockwise thereby imparting continuous motion to the ribbon 33 in a counter-clockwise direction in the drawing considering the entire loop of the ribbon as a whole. Thus, while the ribbon is in use, the face thereof confronting the platen at the printing point is continuously kept supplied with ink which it is preferred to be printers' ink of the proper drying characteristics.

It has been found from experience that best results are obtained when the ribbon 33 is made of the well known synthetic plastic known as vinyl chloride, a material having many of the characteristics of rubber. A commercial form of this material is known under the trade name "Koro seal" and is a polymer of vinyl chloride. Such a ribbon is highly flexible and resistant to the destructive action of the oils which are commonly found in printers' inks which tend to rot rubber. However, equally good results could be obtained with a ribbon made of synthetic rubber of the proper type, by reason of the fact that it is well known that most synthetic rubbers are highly resistant to the rotting action of the oils found in printers' inks.

One of the advantages of using vinyl chloride is that, while it is not as elastic as rubber, it tends to quickly resume its original length when stretched as it might be in the process of inserting such a ribbon in the machine. Also, this plastic is very cheap and the ribbon may be discarded at frequent intervals when too much ink has dried on the surface of the ribbon. It has been found, however, that a ribbon composed of vinyl chloride may be used for a considerable length of time before it must be discarded.

Since the ribbon 33 does not have to be impregnated with ink prior to its installation in the typewriter, it may be inserted without soiling the hands. In removing the ribbon even though it is soiled with ink, it may be grasped with a piece of scrap paper to protect the fingers and torn from the machine and discarded without soiling the operator's fingers. In the event the ribbon breaks during the use of the machine, the loss is practically negligible since the ribbons may be sold for a trifling cost.

It will thus be seen there is a desired advantage in the ribbon mechanism described herein arising from the fact that the ink transfer element which cooperates with the type bars is cheap and may be easily installed without any mess.

When installing the ribbon it is desirable to swing the lever 26 upwardly and rearwardly of the machine and then insert the ribbon in the loops of the ribbon guide 5 in the usual way before looping the ribbon around the front guides 31 and in front of the finger 32. The stretch of ribbon between the right-hand guides 29 and 31 may then be twisted with the finger and the lever 26 restored to its original position. The finger 32 prevents the ribbon from swinging into

the path of the foremost type bars in the type basket.

The ribbon inking mechanism described herein is especially advantageous in machines designed for the preparation of the master sheets used in making photo-offset printing plates by reason of the fact that the inked impressions produced thereby are much clearer and more solid than those produced with conventional fabric ribbons impregnated with ink. The reason for this is that when the types strike through ordinary fabric ribbons, the outline of the characters is not sharp and the bodies of the characters are not uniform in tone because of the fact that the weave of the fabric ribbon is impressed upon the paper and the ink transfer is greatest at the diameter of the threads arising from the greater compression of the fibres of the high spots and hence stronger expressions of ink from the fabrics at these points by the impact of the type bar. When a ribbon such as the one described herein is used its surface is smooth and covered with a uniform film of ink which likewise is uniformly transferred to the paper by the type with a clear, sharp impression as in ordinary printing from set type.

In preparing printing plates from photo-offset master sheets, it is necessary that the characters be clear and sharp and that they be uniformly black as the plates are prepared by photography and it is desired to have maximum contrast in the film. Particularly is this necessary when the master sheet is to be enlarged so that the characters printed by the plate will be larger than the originals. In the past the desired characteristics of the master sheet have been obtained by using carbon paper ribbons instead of inked ribbons but such carbon paper ribbons are quite expensive since they may be used only once and then discarded. When comparing carbon paper ribbons with the unimpregnated ribbons used in the mechanism disclosed herein, there is a desired advantage in the latter from the cost standpoint since the ink may be obtained on a bulk basis and the ribbons themselves will cost only a trifling sum.

While there have been shown and described and pointed out the fundamental novel features of the invention, as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claim.

What is claimed is:

In a machine of the class described, in combination with the typing devices and power actuating means for the typing devices, an endless ink transfer ribbon for inking the faces of the type, means to guide said ribbon past the printing point of said devices, and ribbon feeding and ink transfer means including an ink fountain and an ink transfer roller actuated by said power actuating means for continually feeding said ribbon and at the same time transferring a film of ink of the face of the ribbon confronting the work sheet receiving the impressions of the typing devices.

JOHN L. PETZ.
